UNITED STATES PATENT OFFICE.

CARLOS ALBERTO SCHMID, OF NEW ORLEANS, LOUISIANA.

AUXILIARY FUEL SUPPLY FOR GAS ENGINES.

Application filed October 9, 1923. Serial No. 667,515.

To all whom it may concern:

Be it known that I, CARLOS ALBERTO SCHMID, a citizen of the United States, residing at New Orleans, in the parish of Orleans and State of Louisiana, have invented certain new and useful Improvements in Auxiliary Fuel Supplies for Gas Engines, of which the following is a specification.

10 This invention relates to means whereby an auxiliary supply of fuel may be carried by automobiles for use in the event that the main supply becomes exhausted, and has more particular reference to a tank of 15 relatively small capacity that is adapted to be associated with the usual vacuum tank of the fuel supply system on automobiles using a vacuum tank, and to be installed at a certain convenient place between the carburetor and the main gasoline tank on cars not using a vacuum tank whereby the gasoline in this auxiliary fuel supply tank may be employed when the vacuum tank 20 or main fuel tank has been completely exhausted of its fuel.

25 The main object of this invention is to provide an auxiliary fuel supply for gasoline engines in the form of a tank that is to be associated directly with the outlet of the usual vacuum tank of the engine fuel supply system on automobiles using a vacuum tank, and to be installed at a certain convenient place between the carburetor and the main gasoline tank on cars not using 30 a vacuum tank whereby when the main gasoline supply has become exhausted, the outlet of the auxiliary tank may be opened for allowing the gasoline therein to pass directly to the carburetor for consequently 35 allowing the machine to be driven a sufficient distance so that the fuel supply may be replenished and the motor continued to operate without the usual necessity of having to manually fill the vacuum tank which 40 is in some instances, a relatively difficult matter to accomplish.

45 A still further object of this invention is to provide such an auxiliary tank that is extremely simple of construction and one that may be manufactured and marketed at relatively small cost and installed by those unskilled in the art.

50 With the above and other objects in view, as the nature of the invention will be better understood, the same comprises the novel form, combination and arrangement of

parts hereinafter more fully described, shown in the accompanying drawings and claimed.

In the drawings wherein like reference 60 characters indicate corresponding parts throughout the several views,

Figure 1 is an elevational view of my auxiliary fuel supply when associated with a vacuum tank,

65 Figure 2 is an enlarged vertical sectional view of an auxiliary fuel supply tank constructed in accordance with this invention, and

70 Figures 3 and 4 are enlarged detail cross sectional views taken substantially upon the lines 3—3 and 4—4 respectively of Figure 1.

Now having particular reference to the drawings, 5 indicates any conventional type of vacuum tank or main fuel supply tank 75 that is employed in the usual fuel supply system for gasoline engines and that is equipped at its lower side with the usual externally screw-threaded fuel outlet nipple 6. The usual gasoline supply line between 80 this vacuum tank or supply and the engine carburetor is designated 7 which is equipped at one end with a well known coupling 8 whereby this pipe 7 is operatively connected 85 to said externally screw threaded outlet nipple 6 of the tank 5.

90 In the installation of my novel auxiliary fuel tank this supply line 7 is disconnected from said nipple and my auxiliary tank connected at one end to the tank nipple 95 and at its opposite end to said pipe 7.

95 My invention per se embodies the provision of a cylindrical tank 9 of substantially one gallon capacity and that is open at its upper end and formed at such end with an inwardly extending flange 10 that is formed with spaced screw-threaded openings and upon which is positioned a closure plate 11 that is also formed at its marginal edge with 100 openings for alignment with the before mentioned screw-threaded openings in said flange 10 whereby this cover may be securely fastened to the tank through the medium of set-screws 12; it being noted from a consideration of Figures 1 and 2, that a packing ring 13 is interposed between the cover plate and the upper end of said tank for 105 obvious purposes.

110 This cover plate 11 is formed centrally with an upstanding inlet nipple 14 that is internally screw-threaded at its upper end for threaded engagement with the before

mentioned externally screw-threaded outlet nipple 6 of the vacuum or supply tank 5. Pendant from this cover plate 11 and communicating with said inlet nipple 14 is a
5 relatively elongated flow pipe 15 that extends downwardly within said cylindrical tank 9 and projects through a central opening 16 in the bottom wall thereof. The projecting end of this pipe 15 is externally
10 screw-threaded at 17 for receiving a jamb-nut 18 as well as the usual coupling element 8 of said pipe 7.

The flow pipe 15 is equipped at a point directly above the bottom wall of said cylindrical tank 9 with an inlet 19 that is preferably in the form of an elbow pipe the upper end thereof being so formed as to provide a valve seat complementary with which is a valve 20 that is pivotally carried by one end of a rock lever 21 that is in turn pivoted intermediate its end as at 22 to an upstanding bracket 23 formed upon said elbow pipe 19. The connection between the rock lever 21 and the stem 20' is preferably as shown, that is a sliding connection for allowing movement of the float while the car is in motion without affecting the valve 20 and permitting the fluid to escape. The opposite end of this rock lever 21 is pivoted to the lower end of a rod 24 that carries adjacent its upper end a float 25, the extreme upper end of this rod projecting through an opening 26 in the top cover plate 11 and pivoted to one arm of a bell crank 27. This bell crank is pivoted at 28 to a bracket 29 formed upon said cover plate 11 and pivotally secured to the opposite arm thereof is a push rod designated 30 which extends preferably through an opening in the instrument board of the motor vehicle that is equipped with an operating knob.

In view of the above description it will at once be apparent that the normal position of the valve 20 is open due to the weight of the float 25, but after the device has been installed and the gasoline is al-

lowered to flow therethrough and after the carburetor has become full, the gasoline will back up into the tank 9 until the float 25 rises to cause closing of said valve 20. It will be manifest that should the main gasoline supply become exhausted the push rod 30 may be controlled for consequently forcing downwardly upon the rod 24 for thereby opening the valve 20 and allowing the gasoline from the tank 9 to flow into the carburetor whereby the motor may be operated until the fuel supply is replenished. 55

The specific operation together with the numerous advantages of an auxiliary fuel supply for gas engines of the present type will be at once appreciated by those skilled in the art, and even though I have herein set forth the most practical embodiment of the invention with which I am at the present time familiar, it is nevertheless to be understood that minor changes may be made therein without departing from the spirit and scope of the appended claim. 60 65

Having thus described my invention what I claim as new and desire to secure by Letters Patent is:—

A reserve fuel supply for internal combustion engines comprising a tank having an open upper end and a central opening in the bottom, a cover section for the tank having a cover plate removably secured to the upper open end and formed with an upstanding inlet nipple for adjustment to the outlet nipple on the bottom of a main supply tank, said cover plate being further formed with a depending flow pipe projecting through the opening in the bottom of the tank, means for forming a fluid tight joint between the lower ends of the flow pipe and the tank; the fuel supply line being adapted for connection to the lower end of the flow pipe, and a valve control passing between the interior of the tank and the flow pipe adjacent the bottom of the tank. 90

In testimony whereof I affix my signature.

CARLOS ALBERTO SCHMID.
